UNITED STATES PATENT OFFICE.

EPHRAIM H. FENTON, OF KANSAS CITY, MISSOURI.

GRINDING-MACHINE FOR MOWER AND REAPER KNIVES.

SPECIFICATION forming part of Letters Patent No. 402,152, dated April 30, 1889.

Application filed February 21, 1888. Serial No. 264,865. (No model.)

To all whom it may concern:

Be it known that I, EPHRAIM H. FENTON, a citizen of the United States, residing at Kansas City, in the county of Jackson and State 5 of Missouri, have invented certain new and useful Improvements in Grinding-Machines for Mower and Reaper Knives; and I do hereby declare that the following is a full, clear, and exact description of the same, which will 10 enable others skilled in the art to which it appertains to make and use the same, reference being had to the accompanying drawings, forming a part of this specification.

This invention is an improvement upon the 15 grinding-machine for which Letters Patent of the United States No. 342,789 were granted to me, and bearing date the 1st day of June, A. D. 1886; and it consists, first, in a reciprocal table for the mower-knives, by means of 20 which the blade of the mower-knife may be brought more accurately into grinding relations with the emery-wheel and adjusted gradually in position; second, to enable the cam which holds the blade of the mower-knife 25 to yield when the blade recoils under the application of the grinding-tool; third, to provide an extension for the reciprocating table.

Similar letters of reference indicate corresponding parts in the drawings.

Figure 1 is a view in perspective of my improved grinding-machine, showing the same mounted upon its bed and its relative parts 30 in operative relation. Fig. 2 is a side view of the rod upon which the table for the mower-knives is mounted and is reciprocated, showing the cam, the spring, and the adjusting-screw for regulating the reciprocal movement of the table. Fig. 3 is a plan view of the rack upon 35 the bed of the machine. Fig. 4 is a side view of the upper and lower horizontal rack and the intermediate pinion. Fig. 5 is a perspective view of the end portion of the table for the mower-knives, showing the slot in the end 40 for receiving the extension of said table. Fig. 45 6 is a perspective view of the extensions of the reciprocal table.

In the construction of the invention and upon the base or bed A is mounted a standard, B, the upper end of which is forked, as 50 at b b. The opposite forked ends b b are perforated in a horizontal relation, as at b', and through said perforations is introduced,

so as to turn freely, one end of a shaft, c. Upon the opposite end of the shaft c is mounted an external annular cog-wheel, C, 55 of the proper dimensions to form a driving-wheel. A tool-frame, D, is then formed, consisting of two parallel arms, d d, connected between the opposite ends by transverse bars d' d'. The opposite portions d d, at one end 60 of frame D, are made to fit against the respective outer side portions of the forked ends b b of the standard B, and are perforated in a transverse relation, as at d', to receive the shaft c, which passes through said perforations. The frame D extends from the shaft c radially a short distance beyond the periphery of the wheel C and vibrates freely on shaft c. 65

Between the side of the contiguous portion 70 d of the frame D and the wheel C on shaft c is placed a sleeve, c', and through the end of shaft c which extends beyond the side of the opposite arm, a, is inserted a pin, c'', which pin and sleeve prevent any lateral movement of 75 the wheel C.

In the opposite ends d d of the frame D to that attached to shaft c are joined boxes d', and journaled in a transverse relation in said journal-boxes is a mandrel, d'', which extends 80 to a point beyond the inner side of the wheel C, and upon said mandrel, opposite to and meshing with the cogs on said wheel C, is keyed a gear, d'''.

Upon the mandrel d'', between the opposite 85 arms d d of the tool-frame D, is fitted rigidly the grinding-disk D', which is similar in form to opposite truncated cones joined at their bases, and is preferably made of emery.

Upon the portion of the bed A lying in 90 front of the emery-wheel D' is mounted a horizontal reciprocating table, E, parallel with the shaft d''. In the side portion of table E, opposite the disk D', is made a V-shaped opening corresponding to that between the opposite teeth in the knives of a mower or reaper. 95

For the purpose of enable the table E to be reciprocated between two adjustable points of resistance, and thus enable the grinding to be effected in degrees and to the same extent on 100 the separate teeth, I make, first, two racks, e e, which are placed on the bed A at right angles to and beneath the table E a proper distance apart and in a parallel relation. The

said racks e are retained in their position to each other by transverse bars $e' e^3$, which extend horizontally from one to an opposite rack at one end and at a point intervening, 5 and from the outer side of said racks extend horizontally and at diverging angles from each rack the bars $e^3 e^3 e^4 e^4$. The racks and bars are preferably cast in one piece, and upon the extreme ends of the bars $e^3 e^3 e^4 e^4$ are cast in 10 a vertical relation the standards $e^5 e^5 e^6 e^6$.

To the standards $e^5 e^6$ at their upper ends is attached in a horizontal relation the opposite ends of a rod, e^7 , and a rod, e^8 , is attached in a similar manner to the standards $e^6 e^6$. 15 Upon the under and opposite longitudinal side portion of the reciprocating table E are the lugs $e^9 e^{10}$, which are perforated at their lower ends in a transverse relation to the said table E and at a distance apart corresponding to that of the rods $e^7 e^8$, which rods are passed through the said perforations in said lugs and the table reciprocated thereon. The lugs e^{10} , which are diagonally opposite each other, extend a short distance below the others on the rods $e^7 e^8$. Through the standard e^5 a short distance below the rod e^7 is made 20 a screw-threaded perforation, e^{11} , and in said perforation, from a position on the side near the emery-wheel D, is inserted a thumb-screw, 25 e^{12} , which impinges against the lug e^{10} on that side of the table E. Through the standard e^6 , from a position on the opposite side of the table and below the rod e^8 , is introduced a thumb-screw, e^{14} , which impinges against the 30 lug e^{10} of the table E.

Upon the under side portion of the table E, directly over the racks $e^{15} e^{15}$, two cog-wheels, $f f'$, are then made, which are made to engage with the upper and lower racks $e^{15} e^{15}$ at the 40 respective ends of the table. The cog-wheels $f f'$ are rigidly connected by means of a central shaft, f' , and to said shaft is attached rigidly an operating-handle, F. Upon the side of table E opposite to that having the V-shaped opening for the emery-wheel is cast or formed the support $e^{16} e^{16}$, and on said support is formed a vertical extension, e^{17} , the upper portion of which is cut away at an angle inclined at e^{18} toward the table E. For the 45 purpose of holding the knives a cam, G, is then formed, consisting of a short longitudinal perforated cylinder, g , from the side of which at right angles and between opposite ends extends the horizontal arm g' . The lower portion of the cylinder g is cut away in 50 a transverse relation at an angle of inclination corresponding to that of the portions e^{17} . From the side of the cylinder g opposite to that having the arm g' and at the upper end 55 extends horizontally an arm, g^2 . Through the portion e^{17} of the support e^{16} is then made a vertical perforation, and a bolt, g^3 , having a head, g^4 , is inserted through said perforation on the support and through the cylinder g 60 and a suitable distance above said cylinder, and a cap, g^5 , fitted to the end of said bolt. I

then place a spring, g^6 , on the bolt g^3 , which bears at one end on the cylinder g and the opposite end on the cap g^5 , so that the arm g' is under tension.

For the purpose of lengthening the table E, in the end of said table is formed a longitudinal rabbet, e^{19} , and in a transverse relation to the table E and beneath the said rabbet is formed a cross-bar, e^{20} . I then make an extension, H, for said table E of the same relative width and of any desired length, the opposite ends of which are provided with a lip, h , of the width of the rabbet e^{19} , and which lip is cut away in a horizontal relation a distance nearly one-half of the relative thickness of the said extension H and extending longitudinally to a point between the shoulder h' and the end of the lip equal to the depth of the rabbet e^{19} in the table E. Upon the under side of the extension H of the table, at a point between the shoulders h' and the end of the lip h , are placed the lugs h^2 , which are so far removed from the shoulder h' as to pass within the rabbet e^{19} and permit the extension H to lie in the horizontal plane of the table and prevent its withdrawal in that position.

In the operation of my improved machine the tool-frame D is held by the hand above 95 the plane of the table. The mower-knives are laid upon said table and arranged in regular order, so as to lie opposite the V-shaped opening. The cam G is then turned by means of the handle g^2 , and its portion g' approaches 100 the knives of the mower, and when at right angles with the table E rests upon and retains said knives from removal. The emery-wheel D' is then placed upon the teeth of the mower-knives in position to receive it, and upon the rotation of the wheel C by means 105 of the handle c^3 the recoil of the mower-knives and the table from the grinding-wheel is equally distributed, and any undue concussion of said wheel upon the table or mower-knives, which would otherwise injure the 110 cam, is obviated by its spring.

To make the grinding uniform, the handle F on shaft f' is moved upward and downward, which operates the gear f and reciprocates the table E to and from the emery-wheel D, and in either direction the lugs $e^9 e^{10}$ abut against the ends of the respective thumb-screws $e^{12} e^{14}$, so that as the said screws are adjusted to limit the distance between opposing 120 ends, and also from the sides of the standards $e^5 e^5 e^6 e^6$, and said ends of screws, the movement of the table is controlled in corresponding degrees, so that the edges of the mower-knives are ground equally. Heretofore the 125 mower-knives, which are of considerable length, when laid upon the table were with difficulty kept in a horizontal plane, and in the service of my extension I am enabled to accomplish the change of position of the 130 knives in the path of the emery-wheel with greater dispatch.

Having fully described my invention, what I now claim as new, and desire to secure by Letters Patent, is—

1. In a grinding-machine, the combination, with the base having a suitable standard, of a driving-wheel, a vibrating tool-holder pivotally attached at one end to said standard and having a rotary grinding-tool at its opposite end in power connection with said driving-wheel, a reciprocating table having a suitable support opposite parallel racks upon said base of the machine and upon the under portion of said table, and cog-gear meshing with said racks, means for rotating said cog-gear, and adjustable stops in the path of said table, as described.

2. In a grinding-machine, the combination, with the base having a suitable standard, of

a driving-wheel, a vibrating tool-holder attached at one end to said standard and having a rotary grinding-tool at its opposite end in power connection with said driving-wheel, a table adapted to support the knives to be ground in the path of said grinding-tool provided with a vertical bolt, a cylinder on said bolt provided with a cam at its lower end, radial arms on said cylinder, one of which extends in the plane of and across said table, and a spring on said bolt having one portion connected with the bolt and the opposite portion resting upon said cylinder, for the purpose described.
